Rooms to R.C. Smith Jr. 3

William L. Sanderson of Troy N.Y.
Assignor to R. R. Finch Jr & R. R. Finch Jr of Pekville N.Y.
Letter Patent No. 466 Dated June 22nd 1852.

Dec. 466

The schedule referred to in these Letters Patent and making part of the same.

To all whom it may concern:

Be it known that I Wm L. Sanderson

of Troy in the County of Rensselaer and State of New York have invented a new ornamental design
for a Parlor and Dining Room Stove which I denominate

"The Cottage Air-tight"

and I do hereby declare that the following is a full and exact description of the same referred
being had to the accompanying drawings forming part of this specification in which

Fig. 1 is a front elevation of the stove and Fig. 2 an end elevation of the same.

Fig. 3 is a profile of the sides. Fig. 4 is a plan of the bottom plate

Fig. 5 is a plan of the top plate of the oven and of the top of the body
of the stove, but part of the top plate of the oven is broken away to show the ornament on the top
plate of the body.

Fig. 6 is a top view of the water evaporating vase

Fig. 7 is an elevation of one of the feet looking directly towards it

Similar letters of reference indicate corresponding ornaments and parts
in each of the several figures.

The shape of the bottom plate of the stove is best shown in Figure 4, but

the ornaments upon it are shown in that figure and also in Figure 1. The outer edge is surrounded with a fancy moulding, which at the front, back and sides consists of ornaments A. One part of the front ornament only is finished as that is sufficient to explain the whole and I will here observe that where an ornament is indicated in the drawings by a letter that if the same letter is shown on a part merely in outline, it is to show that the same ornament is continued there.

The moulding on the edge of the bottom plate is ornamented at the corners as shown at B and at the ends of the part which projects in front to form the hearth with ornaments C. Where the side plates are connected with the bottom plate it has a moulding D running all round: the same ornament extends along the plate E which covers the hearth but is merely a continuation. The inner line in figure 4 shows the inside of the moulding D and at the same time shows the horizontal form of the body of the stove which is formed of two side and two end plates uniting at the corners. The upper plate has an ornament F in relief which nearly covers it.

The front and back side plates are both alike each has an ornament G, H, I, J in relief of scroll work, lattice work, and patterns of leaves and flowers. This ornament is shown in Figure 1, but only one half of it is finished in detail as the other half is similar; at each side of these plates near the corners of the stove there is a scroll work ornament K.

The end plates are both alike; except that in one of them is the door but the door is made to imitate part of the plate so that both ends have the same appearance. In the centre of each is an ornament L, M, N in relief of scroll work and patterns of leaves and flowers (shown in Figure 2) this ornament is only half finished in detail as the other half is similar; at the sides of these plates near the corners there are ornaments K, K on the side plates; these are not necessary to show but their position is indicated by the letter. Along the top part of the side and end plates reaching all round the stove, close below the top plate of the body is a moulding O which is best shown in Figure 1.

The top plate of the stove body has a moulding P (see Figures 1 and 5) which extends all round where the ornaments on it, the oven being of elliptical form; it has also an ornament Q in relief near each corner.

The top plate of the oven is surrounded by a moulding R, S, T (see Figures 1 and 5) only one portion of this is finished in the drawing as the remainder is mere repetition of it.

The lid or cover of the oven is surrounded by a moulding U (see Figures 1 and 5) in which Figure a part is shown finished.)

The water basin is best seen in Figure 1; its cover in Figure 6. The form of the vase V is conceal in its general outline and may be better understood by reference to Figure 1 than by description. The foot basin and cover have mouldings a, b, c all of the same character surrounding them; under the bottom of the basin there is a moulding e; the top or handle of the cover is in the form of an open flower.

Des. 466

3
The feet have ornaments g in bas relief representing a cluster of grapes and vine leaves and also the ornaments h, i, j which are best explained by the drawings

What I claim as my invention and desire to secure by Letters Patent is

The ornamental form, design and configuration as herein described and represented of the stove as a whole and also of the several plates, the feet and vase separately
